UNITED STATES PATENT OFFICE

2,120,913

PROJECTILE

René R. Studler, United States Army, Philadelphia, Pa.

Application February 1, 1934, Serial No. 709,346

1 Claim. (Cl. 102—26)

(Granted under the act of March 3, 1883, as amended April 30, 1928; 370 O. G. 757)

The invention described herein may be manufactured and used by or for the Government for governmental purposes, without the payment to me of any royalty thereon.

5 The subject of this invention is a projectile and relates more especially to high velocity long range projectiles.

The main objects of the invention are the production of a projectile that will offer comparatively small frictional resistance to starting motion and travel through a gun barrel, which will effectively seal against the escape of gas past the projectile which is in motion when taking the rifling of the gun, which may be effectively sealed and held against displacement in the cartridge case, which will have desired ballistic characteristics during flight, and which may be used with the present standard rifled barrel.

20 These objects are attained by the proper formation of the projectile, by proper positioning and dimensioning of the steadyng (locating) and rotating (driving) bands and by other novel details of construction.

With the foregoing and other objects in view, 25 the invention resides in the novel arrangement and combination of parts and in the details of construction hereinafter described and claimed, it being understood that changes in the precise embodiment of the invention herein disclosed 30 may be made within the scope of what is claimed without departing from the spirit of the invention.

The spirit of the invention includes all projectiles used in rifled weapons, the fundamentals of 35 design being applicable to projectiles of all calibers regardless of type of ammunition used.

By way of illustration a .30 caliber bullet constructed in accordance with the invention is disclosed in the accompanying drawings, wherein:

40 Fig. 1 is a view in side elevation of a projectile. Fig. 2 is a rear elevation of the same.

Fig. 3 is a longitudinal sectional view of a modified form of the bullet.

Fig. 4 is a similar view of another form.

45 Fig. 5 is a view partly in elevation and partly in longitudinal section of a complete round containing a projectile constructed in accordance with the invention, and

50 Fig. 6 is a longitudinal section of the breech end of a rifle barrel, the position of the round of ammunition being indicated therein in dotted lines.

Referring to the drawings by numerals of reference: The projectile consists of a body 1 of 55 cylindrical formation and slightly in excess of

one and one-half calibers in length. The main portion of the body is slightly less than one caliber in diameter so as to assure that this portion of the projectile will not bear on the lands of the weapon in its passage through the barrel. At the front end of the body a steadyng (locating) band 2 is provided of a diameter sufficiently greater than one caliber to assure holding the forward portion of the projectile in such position that the longitudinal axis of the projectile will coincide with that of the bore and to assure seating of the band in the forcing cone in rear of the origin of the rifling. This band is herein shown as one-sixth of a caliber in width with a beveled forward edge. This exact dimension is not essential as the purpose and object of this band is to form an effective initial gas seal and to guide and steady the projectile during its passage through the gun barrel, it is therefore essential that this band be as light as is consistent with effective initial gas sealing and steadyng of the projectile. A rotating (driving) band 3 is provided on the projectile and is situated slightly in excess of one caliber from the forward edge of the beveled portion of the band 2. This band is also preferably formed with a beveled forward edge and is substantially one-third of a caliber in width. To the rear of the rotating (driving) band 3 the body may be formed with a tapered or boat-tail end 4 in the base of which may be formed a cavity 5 of slightly less than one-third of a caliber in depth and of as great a volume as is consistent with the strength of the walls of the base of the projectile.

The head 6 of the projectile is of elongated 35 ogival formation, substantially one and one-half calibers in length and the arcs of curvature are struck with radii of seven and six-tenths calibers from points as centers located in a line perpendicular to the longitudinal axis of the projectile 40 and situated slightly more than one caliber, in this instance .307", to the rear of the base of the ogive.

From the foregoing it will be evident that 45 only the bands 2 and 3 take the rifling of the gun barrel. Now band 2 is made narrower than band 3 in order to reduce the pressure required to force it into the rifled barrel. The projectile, therefore, is enabled to begin its travel at a relatively early stage of the combustion of the powder charge. The volume of the powder chamber is thus increased at an early stage of combustion, and therefore larger powder charges can be used with great increase in velocity of the bullet without exceeding permissible pressures.

In the form illustrated in Fig. 3 an armor piercing bullet is shown which is 4.65 calibers in length with a pointed head $6a$ 2.65 calibers in length struck with a radius of 8 calibers in length. The body $1a$ of the bullet is substantially 1.3 calibers in length with a boat-tail base $4a$ substantially $\frac{2}{3}$ of a caliber in length. The steadyng (locating) band $2a$ is $\frac{1}{6}$ caliber in width and the rotating (driving) band $3a$ is $\frac{1}{3}$ of a caliber in width. The forward edges of both bands are beveled. The bodies of both bullets, ball and armor piercing, have the same diameters and the bands are of equal diameter so that aside from variations in the point or nose and base, both bullets are alike on outside contour.

With an armor piercing bullet such as illustrated in Fig. 3, the core 11 may be heavier than in the standard bullet and the bullet as a whole still be lighter by reason of the fact that the jacket is much lighter. This lightening of the jacket is made possible by reason of the fact that there is very reduced frictional contact between the bullet and walls of the rifle barrel and consequently less tendency to strip the jacket from the bullet. The heavy core which is the element of the bullet which does the armor piercing has greater penetrative ability and renders the projectile more effective for the purpose for which it is intended.

The modified form of projectile illustrated in Fig. 4 has the base or boat-tail 4 left off but is in all other respects similar to the one shown in Fig. 3, or could be the same as that shown in Fig. 1.

As seen most clearly in Fig. 5, the neck of the cartridge case 7 is crimped behind the steadyng (locating) band 2 or $2a$ as at 8 , thereby forming a perfect construction for sealing the round against moisture and also presenting a shoulder

which prevents forcing the bullet rearwardly into the cartridge case, which is of great advantage when using the round with that class of machine guns which resize each round as it is fed to the gun, often causing short round stoppages.

As illustrated in Fig. 6, the cartridge case 7 seats in the cartridge chamber of the gun with the steadyng (locating) band 2 or $2a$ forced into the forcing cone 9 to form an initial gas seal and hold the projectile properly centered. The nose of the projectile is positioned between the lands 10 without contact therewith so that the projectile is in motion before the engraving by the lands of the light steadyng (locating) band takes place and has gained still further momentum before the rotating (driving) band is engraved by the lands.

The term "caliber" as used herein will be understood to mean the bore diameter of the weapon on which the projectile is intended for use.

The term "beveled" as used herein will be understood to mean a broken forward face on the bands which may be a plane incline, a convex surface, or a concave surface the intent being to avoid a forward surface on the bands lying in a plane at right angles to the axis of the projectile.

I claim:

A projectile including a body substantially one and two-thirds calibers in length, the diameter of the body less than one caliber, bands at the front end and adjacent to the rear of the body, and a pointed ogival head substantially one and eight-tenths calibers in length, the curve of the ogive an arc struck from a point as center located on a line perpendicular to the longitudinal axis of the projectile positioned substantially one caliber to the rear of the base of the head.

RENÉ R. STUDLER.
